Primary Examiner—Martie K. Holtje[57] **CLAIM**

The ornamental design for the binder cover, as shown and described.

DESCRIPTION

FIG. 1 is a front perspective view of a binder cover showing my new design;

FIG. 2 is a rear perspective view thereof;

FIG. 3 is side elevational view thereof;

FIG. 4 is a side elevational view of the side opposite that shown in FIG. 3;

FIG. 5 is a top plan view thereof;

FIG. 6 is a bottom view thereof;

FIG. 7 is a front elevational view thereof;

FIG. 8 is a rear elevational view thereof;

FIG. 9 is a perspective view of the binder cover shown in an open position;

FIG. 10 is a perspective view of the side opposite that shown in FIG. 9;

FIG. 11 is a perspective view of the binder cover shown configured as a reading support;

FIG. 12 is a perspective view of an alternate embodiment shown in an open position; and,

FIG. 13 is a perspective view of the side opposite that shown in FIG. 12.

The ring binder, fastener structure and sheet of paper depicted by means of broken lines in FIGS. 9 through 13 have been shown for illustrative purposes only and form no part of the claimed design.
